ADOLF ROHRBACH, OF WILMERSDORF, NEAR BERLIN, GERMANY, ASSIGNOR TO ROHRBACH PATENTS CORPORATION, A CORPORATION OF DELAWARE

MONOPLANE FLYING BOAT

Application filed July 21, 1927, Serial No. 207,393, and in Germany July 13, 1926.

The invention relates to a monoplane flying-boat, characterized by the boat-hull carrying the tail plane unit and wing, which latter supports the driving means, and being provided with a sharp-edged bow and a slightly inclined and elevated stem; the forecastle, containing one or more cockpits for the crew, preferably considerably overtopping the remaining deck portion and substantially merging, into the leading edge of the wing, in the direction of the inclination of the latter, whilst the wing trailing edge ends on a level with the central boat deck or somewhat below the same. With the forecastle curved, its lateral edges merge into the bottom surface of the wing at the wing leading edge, whilst the central portion of the forecastle is attached to the top surface of the wing.

According to the present invention it is possible to design a monoplane flying-boat of perfect seaworthiness and able to cut the waves of a heavy sea without washing over the forecastle. Further advantages consist in that this new type of flying-boat has, owing to its very small air resistance, excellent flying properties, and permits of good and unobstructed vision in substantially all directions.

For a better understanding of the invention, reference may be had to the accompanying drawing which show, by way of example, several embodiments of the present invention, wherein:

Figs. 1 and 2 represent one embodiment in side elevation and plan view.

Fig. 3 is a front elevation with indicated body planes.

Fig. 4 is a front view of a boat with modified bow.

Figs. 5 and 6 are further forms of embodiments in side elevation.

The hull of the monoplane seaplane according to Figs. 1 and 2 consists of a boat-body *a*, carrying at the rear part the tail plane unit *b* and substantially centrally thereof the wing *c*. High above the latter two engines are arranged laterally and symmetrically to the vertical central plane of the craft and supported on struts. Underneath each wing half a stabilizing float *d* is arranged and

braced either against the wing alone or against both wing and hull, said float functioning to impart to the floating craft a rather great metacentric height, and to the craft at starting a considerable dynamic buoyancy. 55

The boat is comparatively narrow and elongated. Two steps *e*¹, *e*² are provided. The bottom part *f*¹ in front of the first step *e*¹ is considerably inclined towards the keel *g*, which merges towards the more elevated chime, into a curve *h* (concave downwardly). This construction of the bow facilitates take off and alighting by deviating the water current. The bottom parts (*f*², *f*³) aft of the steps are rather flat-surfaces with very small, 65 if any, inclination.

The keel *g* of the bottom *f*¹ terminates, with a sharp-edged bow, into a rather precipitous erect stem *i*, the top part of which is situated above the dotted line indicating the level of 70 the central and rear boat-deck *j*, so that the forecastle *k* overtops or projects above the level of the latter. The forecastle edges *k*¹ merge into the wing bottom surface, close to the leading edge *c*¹ of the wing, whilst the vertex of the forecastle curvature is situated in the same plane as the wing top surface. *k*² indicates the pilot's and mechanic's cockpit. The wing trailing edge *c*² terminates below the central boat deck *j*. 80

According to Fig. 3 the side surfaces of the bow are substantially straight with but little inclination to the vertical. If it seems advisable the bow can be designed as pronounced cruiser bow, by using curved tapered bow 85 frame members in order to obtain the extensively overtopping or overhanging forecastle *k*, which prevents the waves and spray water washing over. Fig. 4 is an embodiment of the said form of construction. The stem *i* can, 90 with either form of construction, be curved or inclined forwardly, as per Fig. 1, dotted line, instead of being straight up.

The form of construction represented in Fig. 5 shows, a boat of the general construction shown in Fig. 1 but with the trailing edge *c*² of the wing *c* terminating in the plane of the deck *j*. This is effected by elevating the forecastle *k* still further with reference to the level of the deck *j*, the edges *k*¹ of 100

the forecastle situated in the plane of the wing chord. The vertex of the forecastle curvature ends in the central air-threads convergency point of the wing (c^3). The latter arrangement is recommended in the event that special value should be attached to favourable air flow conditions, whereas, to obtain the best possible view backwards, the vertex of the curvature should preferably be situated in the plane of the wing top surface.

Another advantageous feature of this form of construction resides in the wing c being detachably attached in the plane of the boat deck, so that the wing bottom surface and deck plane are continuous. The junctures or attaching means are represented diagrammatically by c^4 , preferably including screw devices and are situated in the planes of two wing main girders. The float bracing struts are carried to the main girders as illustrated.

According to the form of construction of Fig. 6 an elongated boat body is represented, with a wing consisting of a box-shaped central portion and leading- and trailing edges imparting the final sectional shape to the wing, said central portion being accommodated in an aperture or recess, opening towards the deck, formed in the corresponding higher raised boat-body. The connection of boat and wing should, with this latter arrangement, also be detachable, so that, with the wing attached, the transverse walls of the latter carry the forces occurring in the boat deck beams. In this case the deck is substantially straight, from bow to stern, the lines thereof being only slightly bent with the wing top surface, the forecastle and the rear part of the deck situated in substantially the same plane.

It is not essential, according to the invention, whether the wing is entirely of the cantilever type or braced or supported by means of wires or struts. If desired, the bow can be made, with every form of construction, so long that in front of the pilot's cockpit k^2 another hatchway for one member of the crew can be arranged at a suitable distance, as shown in Fig. 6.

Of course the edges of the forecastle need not be attached to or merge into the wing chord in case of the bow walls merging into the forecastle with continuous curvature. In another form of construction the edges of the curved forecastle terminates in the central air thread convergency point of the vertex in the wing top surface. Pusher- or tractor screws can be provided in all cases with equal efficiency.

After having thus described the nature of my said invention and in what manner the same is to be performed, I declare that what I claim is:

1. In a monoplane flying boat the combination of a boat hull of elongated form having a bow terminating in a sharp cutting edge

with a high stem forming with the keel of the boat a sharp inclination, the rear boat deck being substantially coplanar and the forward deck elevated above the level thereof, with wings directly attached to the hull and having a thick section at their junction therewith, and said wings having their uppermost surfaces substantially above the plane of the rear deck.

2. A flying boat of the character set forth in claim 1 wherein the elevated front deck is formed with a curved surface, its upper surface merging into the nose of the wing.

3. A flying boat of the character set forth in claim 1 wherein the elevated front deck is formed with a curved surface, the upper part of which merges into the center of the leading edge of the wing.

4. A flying boat of the character set forth in claim 1 wherein the elevated front deck is formed with a curved surface, and the edges formed by the front deck and side walls of the hull substantially intersect the front end of the wing chord.

5. A flying boat of the character set forth in claim 1 wherein the elevated front deck is formed with a curved surface, the uppermost part of which forms substantially a continuation of the uppermost surface of the wing.

6. A monoplane flying boat having a sharp-bowed hull adapted to take load substantially throughout its length and to carry the tail plane unit, with the plane carrying the engine or engines and resting on the hull, and with a high stem joining the keel with a sharp curve, the forward deck, open for a cock-pit or cock-pits, being raised above the level of the mid ship and aft deck, said forward deck merging into the fore part of the wing, and the trailing edge of the plane terminating at a point at least not above the level of the mid ship portion of the deck.

7. In a monoplane flying boat the combination of a boat hull of elongated form having a bow terminating in a sharp cutting edge with a high stem forming with the keel of the boat a sharp inclination, with the monoplane wings directly attached to the hull at the upper deck and having thick sections at their junction therewith and a power plant elevated substantially above the level of both the boat hull and the monoplane wings.

8. In a monoplane flying boat of the character set forth in claim 7 wherein the hull is of narrow elongated form and has substantially straight vertical side lines from the chines to the rim of the boat.

9. In a monoplane flying boat the combination of a boat hull of elongated form having a bow terminating in a sharp cutting edge with a high stem forming with the keel of the boat a sharp inclination, the forward deck of the hull being elevated above the level of the aft deck, with the monoplane wings di-

rectly attached to the hull and having thick sections at their junction therewith, the elevated fore deck merging into the wings.

10. A flying boat of the character set forth in claim 9 wherein the elevated forward deck which merges into the wing section is formed with other than a plane surface, the rim of the fore deck approximately intersecting at its rear ends the wing chord.

10 11. A monoplane of the character set forth in claim 9 wherein the wings are disposed above the level of the aft deck, the upper surface of the fore deck merges into the leading edge of the wing, the rim of the fore deck formed by the fore deck and side walls lying in the plane of the wing chord and the wing chords having a positive angularity with reference to the edges of the aft deck.

12. In a monoplane of the character set forth in claim 9 wherein the wings are elevated above the plane of the level of the aft deck with their root portions demountably attached to the hull, the upper surface of the elevated fore deck merging into the leading edge of the wing, the fore deck rim formed by the front deck and side walls of the hull being approximately in the direction of the wing chord.

13. In a monoplane flying boat the combination of an elongated boat hull having a bow terminating in a sharp cutting edge with a high stem forming with the keel of the boat a sharp inclination and the side walls of the hull extending without sharp breaks in contour from the chines to the deck, the latter being substantially planar at its after part and the fore deck being elevated above the level of said after deck, with the monoplane wings directly attached to the hull and having thick sections at their junction therewith, said monoplane wings having the major part of their section positioned above the level of the after deck and bridging the gap between the elevated fore deck and the aft deck, and a power plant supported substantially above the level of both the monoplane wings and the flying boat, the fore deck containing means for observation by the crew and merging into the forward part of the wing.

50 14. A monoplane of the character set forth in claim 13 wherein the rims at the fore deck formed by the fore deck and the side walls of the hull lie in an approximate prolongation of the wing chord and the monoplane wings are of full cantilever construction.

15. A flying boat of the character set forth in claim 13 including two displacement pontoons disposed laterally of the hull which functions both as transverse stabilizing floating means and hydro-dynamic and buoyant devices for taking off.

16. A flying boat of the character set forth in claim 13 including two displacement pontoons disposed laterally of the hull which function both as transverse stabilizing float-

ing means and hydro-dynamic and buoyant devices for taking off, and wherein the boat hull is provided with a step in the vicinity of the wings, the chines are elevated above the keel and the surface of the boat hull between the chines and the keel are concaved downwardly.

17. A flying boat of the character set forth in claim 9 having an arched forward deck whose sides join the under surface of the plane, its crest joining the vertex of the nose of the plane.

18. A flying boat of the character set forth in claim 9 having an arched forward deck whose sides join the under surface of the plane, its crest joining the top of the plane, and wherein the monoplanes are detachable from the hull with their under surfaces flush with the deck, the deck portion under the plane being at the angle of incidence of the plane.

19. In a monoplane flying boat the combination of a boat hull of elongated form having a bow terminating in a sharp cutting edge and having a high stem forming with the keel of the boat a sharp inclination, the forward deck of the hull being elevated above the level of the aft deck, with the monoplane wings directly attached to the hull and having thick sections at their junction therewith, the elevated fore deck merging into the wing leading edge vertex the latter being the central air-flow convergency point at horizontal flight.

20. A monoplane flying boat including a boat hull of elongated form having a forward deck which is elevated above the level of the aft deck, monoplane wings attached to the hull deck the peripheral edges of the fore deck being downwardly inclined in the rearward direction with reference to the rear deck to form an angle with the edges thereof less than 180°.

21. In a monoplane of the character set forth in claim 20 wherein the peripheral edges of the fore deck form a continuation of the wing chord.

In testimony whereof, I have signed my name to this specification.
